Primary Examiner—Janice E. Seeger

(21) Appl. No.: **29/231,146**

(57) **CLAIM**

(22) Filed: **Jun. 1, 2005**

I claim the ornamental design for an extendible table, as shown and described.

(30) **Foreign Application Priority Data**

Dec. 1, 2004 (EM) 000269873-0016

DESCRIPTION

(51) **LOC (8) Cl.** **06-03**

FIG. 1 is a perspective view of an extendible table prior to extension showing my new design;

(52) **U.S. Cl.** **D6/430; D6/480**

FIG. 2 is a front elevational view thereof;

(58) **Field of Classification Search** D6/480-489,

FIG. 3 is a left side elevational view thereof;

D6/495-499, 422-426, 511, 429-431; 108/150,
108/153.1, 155, 156, 157.1, 161, 157.18,
108/69, 71, 75, 76; 248/188, 188.1

FIG. 4 is a perspective view of the extendible table in a
